UNITED STATES PATENT OFFICE.

NIELS WASILIUS GUDMUNDSON, OF SALT LAKE CITY, UTAH.

ELEVATOR BRAKE.

Application filed August 1, 1921. Serial No. 488,929.

To all whom it may concern:

Be it known that I, NIELS WASILIUS GUDMUNDSON, a citizen of the United States, residing at Salt Lake City, in the county of 5 Salt Lake and State of Utah, have invented certain new and useful Improvements in Elevator Brakes; and I do declare the following to be a full, clear, and exact description of the invention, such as will enable 10 others skilled in the art to which it appertains to make and use the same.

My invention relates to improvements in elevator brakes and has for its principal object to provide a comparatively simple and 15 inexpensive, yet a highly efficient and reliable brake operated by spring-pressure to hold the elevator against movement whenever desired, electrical means being preferably employed for holding the brake shoes 20 in inactive position, against the action of their operating spring or springs.

With the foregoing in view, the invention resides in the novel subject matter herein-after described and claimed, and shown in 25 the accompanying drawings.

Figure 1 is a side elevation partly in vertical section, showing the application of my invention.

Figure 2 is a horizontal vertical view as 30 indicated by the irregular line 2—2 of Fig. 1.

Figure 3 is a vertical sectional view as indicated by line 3—3 of Fig. 1.

Figure 4 is an enlarged vertical section on line 4—4 of Fig. 2.

Figure 5 is an enlarged sectional view of 35 the switch employed for controlling the brake-releasing means.

In the drawings above briefly described, the numeral 1 designates a conventional 40 form of elevator having the usual vertical guide tracks 2. A horizontally elongated metal frame 3 is suitably secured beneath the elevator floor, said frame including upper and lower horizontal end plates 4 and 5 and 45 vertical bars 6 which extend between and are secured to said plates. Riveted or otherwise rigidly secured to each of the bars 6, is a brake shoe 7 from which a bolt 8 extends laterally. A movable brake shoe 9 is a slidably mounted on each bolt 8 and the outer 50 face of each shoe 9 is formed with a non-circular shallow recess 10 which opens through its inner edge. Each recess 10 receives the enlarged outer end 11 of a horizontal lever 12, each of the lever ends 11 being provided with a bolt receiving opening

as shown clearly in Fig. 4. Bearing against the outer side of each of the lever ends 11 is a coiled spring 13 which surrounds the bolt 8, the outer end of the spring being positioned in contact with a washer 14 which is held upon the bolt by a nut 15 and a jamb-nut 16, whereby the strength of the 60 spring may be varied as desired.

The levers 12 are preferably supported by 65 vertical shafts 17 which extend between and are secured to the plates 4 and 5, said shafts being spaced from the bars 6 as indicated clearly in Figs. 1 and 2. The inner ends of the levers 12 are suitably connected with the 70 core 18 of a solenoid 19 having a suitable controlling switch which is preferably operated by foot. The solenoid is used to normally hold the brake shoes from contact with the tracks 2 and the moment the current is cut off from said solenoid, the springs 13 move said shoes into binding frictional contact with the tracks to lock the elevator against descent, said shoes being preferably 75 provided on their inner sides with fiber or 80 other friction blocks 20.

To prevent the springs 13 from acting too suddenly upon the brake shoes and thereby bringing the elevator to a stop with a jerk, I preferably employ a suitable retarding device such as an oil dash pot 21 which is 85 connected with the inner ends of the levers 12.

The switch for controlling the solenoid 19 is shown most clearly in Fig. 5, said switch 90 comprising a pair of spaced contacts 22 adapted to be bridged by a plug 23 which is normally raised by a spring 24 but may be depressed by the foot whenever desired, being provided at its upper end with a foot 95 plate 25 for this purpose. As long as the plug 23 is held in engagement with the contact 22, the solenoid holds the levers 12 in brake-releasing position but the moment the spring 24 is permitted to raise the plug 23, 100 the circuit through the solenoid is broken with the result that the springs 13 act to apply the brakes. The plug 23 is preferably mounted so that it may be entirely removed, thereby preventing unauthorized 105 persons from releasing the elevator brakes and operating the elevator.

From the foregoing, taken in connection with the accompanying drawings, it will be seen that a simple and inexpensive arrangement of parts has been provided for performing the required work and particular 110

attention is directed to the compact construction used. Attention is also invited to the fact that the lever ends 11 are held in their respective recesses 10 by the coiled 5 springs 13 and since said recesses are of non-circular form, they prevent rotation of the movable brake-shoes 19 upon the bolt 8, which is very desirable. In fact, rotation of said shoes would prevent the brake from 10 functioning properly.

Since excellent results may be obtained from the details disclosed, they are preferably followed. It is to be understood, however, that within the scope of the invention 15 as claimed, numerous minor changes may be made.

I claim:

1. An elevator brake comprising a brake shoe adapted to be fixedly mounted on an 20 elevator at one side of one of its guiding tracks, a bolt extending laterally from said fixed shoe, a movable shoe slidable on said bolt for disposition at the other side of the track, a spring mounted on said bolt for 25 forcing said movable shoe against the track, a lever for moving said spring to an inactive position, and means for operating said lever.

2. An elevator brake comprising a brake 30 shoe adapted to be fixedly mounted on an elevator at one side of one of its guiding tracks, a bolt extending laterally from said fixed shoe, a movable shoe slidable on said

bolt for disposition at the other side of the track, the outer side of said movable shoe 35 having a shallow non-circular recess which opens through its inner edge, a lever at right angles to said bolt having one end fitting into said recess to prevent rotation of said movable shoe, a spring mounted on 40 said bolt and bearing against said lever end to hold it in said recess and to force the movable shoe toward the track, and means for mounting said lever on the elevator for use to retract said spring. 45

3. An elevator brake comprising a horizontally elongated frame having upper and lower horizontal plates at one end and a vertical bar extending between and secured to said plates, a vertical shaft spaced inwardly 50 from said vertical bar and connected at its ends to said plates, a fixed brake shoe secured to said vertical bar and adapted to engage one side of one of the elevator tracks, a bolt extending laterally from said fixed shoe, a spring-pressed shoe mounted on said bolt to engage the other side of the track, a spring-contracting lever supported by said shaft and having one end operatively associated with the spring of said spring-pressed 55 shoe, and means carried by said frame for operating said lever.

In testimony whereof I have hereunto set my hand.

NIELS WASILIUSS GUDMUNDSON.
